(57) **CLAIM**

An ornamental design for a button applicator device, as shown.

DESCRIPTION

FIG. 1 is a perspective view of the present invention.

FIG. 2 is a right view of the present invention.

FIG. 3 is a left view of the present invention.

FIG. 4 is a top view of the present invention.

FIG. 5 is a bottom view of the present invention.

FIG. 6 is a front view of the present invention; and,

FIG. 7 is a back view of the present invention.

1 Claim, 5 Drawing Sheets

FIG. 1

FIG. 2

FIG. 3

FIG. 4

FIG. 5

FIG. 6

FIG. 7
